CLAIM

The ornamental design for a shoe as shown and described.

DESCRIPTION

FIG. 1 is a bottom rear perspective view of a shoe showing my new design;

FIG. 2 is a bottom view thereof;

FIG. 3 is a bottom front perspective view thereof;

FIG. 4 is an enlarged view of the claim as shown in FIG. 1 with environment removed for clarity purposes; and,

FIG. 5 is an enlarged view of the claim as shown in FIG. 3 with environment removed for clarity purposes.

The broken line immediately adjacent to and surrounding the shaded area defines the peripheral bounds of the claimed design and forms no part thereof. The broken lines depicting the remainder of the shoe form no part of the claimed design.
